UNITED STATES PATENT OFFICE.

WILLIAM J. LAFFEY, OF CHICAGO, ILLINOIS.

BULKHEAD.

Application filed February 1, 1923. Serial No. 616,226.

To all whom it may concern:

Be it known that I, WILLIAM J. LAFFEY, a citizen of the United States, and a resident of the city of Chicago, county of Cook, and 5 State of Illinois, have invented certain new and useful Improvements in Bulkheads, of which the following is a specification.

My invention relates to improvements in bulkheads especially designed to be used in 10 connection with freight cars and has for its principal object the provision of an improved construction of this character which will serve as a simple and efficient brace for merchandise within the freight car. 15 Among other objects of the invention is the provision of a bulkhead which can be conveniently moved and adjusted into bracing position and be moved out of bracing position when the freight car is used for 20 porting freight not requiring the provision of a brace to retain the freight from creeping or sliding during transit.

Other objects will appear hereinafter.

The invention consists in the combinations 25 and arrangements of parts hereinafter described and claimed.

The invention will be best understood by reference to the accompanying drawings forming a part of this specification, and in 30 which,

Fig. 1, is a vertical cross sectional view of a freight car showing a bulkhead, embodying the invention, associated therewith;

Fig. 2, is a sectional view taken substantially on line 2—2 of Fig. 1;

Fig. 3, is a sectional view taken substantially on line 3—3 of Fig. 1;

Fig. 4, is a sectional view similar to that illustrated in Fig. 3;

Fig. 5, is a side elevational view of the bulkhead as it appears when out of bracing position;

Fig. 6, is a sectional view of the bulkhead taken substantially on line 6—6 of Fig. 1;

Fig. 7, is a sectional view taken substantially on line 7—7 of Fig. 6;

Fig. 8, is a sectional view taken substantially on line 8—8 of Fig. 3; and

Fig. 9, is a perspective view of a lock pin 50 embodied in the invention.

Referring to the drawings, A indicates a freight car and B indicates the bulkhead embodying the invention. The bulkhead comprises a supporting member 10 carried by and having threaded engagement with

a stud shaft 11, said stud shaft 11 being carried by a truck 12 comprising grooved wheels 13 adapted to ride on a track 14 traversing the freight car and carried by 60 the side walls thereof.

The lower extremity of the member 10 is adapted when the bulkhead is in bracing position to pass into a socket 10' formed in a block 11' embedded in the floor 12' of the freight car, there being a collar 13' carried 65 by the member 10 adapted to rest on the block 11'.

Mounted for slidable movement longitudinally with respect to the member 10, are supporting brackets 15 having lock pins 16 for 70 engagement with sockets 17 formed in the member 10, the lock pins 16 being manipulated by caps 18 having integral finger gripping portions 19. The lock pins 16 are under control of spring members 20. As 75 shown in Fig. 7, a groove 21 is formed in the member 10 into which the lock pins 16 are adapted to work when the brackets 15 are moved, this construction being such that the brackets are held against circumferential 80 movement with respect to the member 10.

Pivotedly carried by each of the brackets 15 are brace or spaced partition members 22, formed of suitable material that will best serve the purpose, preferably of malleable iron for obvious reasons. In Fig. 1 of the drawings the braces are shown in bracing position and when in this position their outer extremities are adapted to pass into recesses 23 formed in a plate 24 embedded 85 in the door jambs 25 of the freight car. The ends of the braces are confined in the recesses by plate members 26 mounted for slidable movement on the exposed faces of the members 24, there being slots 27 formed 90 in the plates 26 having threaded bolts 28 working therein to permit the sliding movement of the plates. Entrance slots 29 are formed in the plates 26 and are adapted to register with the recesses 23 to permit the 95 entrance of the extremities of the braces therein, the plates 26 being in their uppermost position as indicated in Fig. 4 when the entrance slots register with the recesses, the plates being held in such position by 105 pins 30 carried by chains 31 fixed to the door jamb as clearly shown in Fig. 4, said pins being insertable in holes 31'. After the ends of the braces are passed into the recesses, the pins 30 are removed and the 110

plates permitted to drop down into a position such that will close the entrance of the recesses, as best shown in Fig. 3.

In Fig. 5, the bulkhead is shown out of bracing position. To move the bulkhead from bracing position, the pins 16 are disengaged from the sockets 17 and the brackets moved along the member 10 to permit the folding of the braces 23 to a position parallel with respect to the side of the member 10, and tied in such position by chains 32. When the brackets and braces are in the position illustrated in Fig. 5, a lug 32' supports one of the braces as indicated at 33, and the bracket carrying that brace supports the adjacent bracket which in turn supports one of the braces of other brackets, as indicated at 33'. This bracket in turn supports the top or adjacent bracket as shown, the braces by means of the chains are prevented from flopping around when the train is in transit.

After the supporting brackets and braces have been arranged as illustrated in Fig. 5, the member 10 is rotated, threaded on the stud shaft 11 drawing the lower extremity thereof from engagement with the socket 10'. After this has been accomplished, the bulkhead is carried by means of the truck 12 and track 14 over to one side of the freight car and fastened in position against the wall thereof by means of a chain 35 having one end fixedly secured to the wall and the other end releasably secured to an eyelet (not shown).

It is apparent from the description herein that I provide a bulkhead simple in structure and one which can be moved and adjusted into and out of bracing position, the manner of moving the bulkhead and adjusting the same in bracing position being obvious from the description herein and by reference to the drawings.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent, is:

1. A structure of the class described including a supporting member, and brace members carried by the supporting member for movement longitudinally with respect thereto and for vertical pivotal movement.

2. A structure of the class described including a movable supporting member, and brace members carried by the supporting member for movement longitudinally with

respect thereto and for vertical pivotal movement.

3. A structure of the class described comprising a supporting member extending upright from a floor, brackets carried by said member, and brace members carried by said brackets for vertical pivotal movement.

4. A structure of the class described comprising a movable supporting member, brackets carried by said member, for movement longitudinally with respect thereto, and brace members carried by said brackets for vertical pivotal movement.

5. A bulkhead for the purposes herein set forth including a vertical supporting member, transverse brace members carried by said supporting member and adapted to be swung vertically into and out of bracing position, and means for locking said brace members in bracing position.

6. A bulkhead for the purposes herein set forth including a member having a socket formed therein, a supporting member having one end mounted in the socket when in operative position, brace members carried by said supporting member, and means for moving said supporting member vertically, when rotated thereon to bring the end thereof out of the socket to permit moving of said member and said brace members.

7. A bulkhead for the purposes herein set forth including a member having means for bracing freight and adapted to be moved into and out of bracing position, a member having a socket formed therein for the reception of an end of said member when in bracing position, and means carrying said first named member and provided with threaded means for lifting the end of the member out of the socket to permit moving said member.

8. A bulkhead for the purposes herein set forth including a supporting member, bracing means carried by said member and adapted to be swung vertically and adjusted longitudinally with respect thereto out of bracing position, and means for locking said bracing means in such position.

9. In combination with a freight car, recessed members embedded in the door jambs of said freight car, a supporting member, and bracing members carried by said supporting member and having their outer extremities confined in the recesses of said first named member when in bracing position.

10. In combination with a freight car, recessed members embedded in the door jambs of said freight car, a supporting member movable transversely with respect to said car, and bracing members carried by said supporting member and having their outer extremities confined in the recesses of said first named members when in bracing position.

11. In combination with a freight car, re-

- cessed members embedded in the door jambs of said freight car, a supporting member, and bracing members carried by said supporting member for vertical, pivotal movement and having their outer extremities confined in the recesses of said first named members when in bracing position.
12. In combination with a freight car, recessed members embedded in the door jambs of said freight car, a supporting member movable transversely with respect to said car, and bracing members carried by said supporting member for vertical, pivotal movement and having their outer extremities confined in the recesses of said first named members when in bracing position.
13. In combination with a freight car, of recessed members fixed to the door jambs of the car, a bulkhead comprising pivotally mounted bracing members having their outer extremities confined in the recesses of said first named member when in bracing position.
14. In combination with a freight car, recessed members fixed to the door jambs of the car, a bulkhead movable transversely with respect to the car and including members having their outer ends mounted in the recesses of said first named members.
15. In combination with a freight car, recessed members fixed to the door jambs of the car, a bulkhead movable transversely with respect to the car and including members having their outer ends mounted in the recesses of said first named members, and means for locking the ends of said members in said recesses.
16. In combination with a freight car, recessed members fixed to the door jambs of the car, a bulkhead movable transversely with respect to the car and including members having their outer ends mounted in the recesses of said first named members, and means for releasably locking the ends of said members in said recesses.
17. In combination with a freight car, of a track traversing said car, a supporting member adapted to ride on said track, and a bulkhead carried by said supporting member to be moved to the side of said car and comprising a support and bracing members carried thereby for vertical pivotal movement.
18. In combination with a freight car, of a track traversing said car, a supporting member adapted to ride on said track, and a bulkhead carried by said supporting member comprising a support and bracing members pivotally carried thereby, and recessed members fixed to the door jambs of the freight car for the reception of the outer ends of said bracing members.
19. In combination with a freight car, of a track traversing said car, a supporting member adapted to ride on said track, and a bulkhead carried by said supporting member comprising a support and bracing members pivotally carried thereby, recessed members fixed to the door jambs of the freight car for the reception of the outer ends of said bracing members, and plates mounted for slidable movement on said recessed members and having slots adapted to register with the recesses of said members to permit the passage of the ends of said bracing members therein, said plates being adapted to lock said ends in said recesses.
20. A bulkhead for the purposes herein set forth including a supporting member mounted for movement transversely with respect to a freight car and having a longitudinally extending groove formed therein, brackets having pin members working in said groove and adapted to engage sockets formed in said member for holding said brackets in operative position, and bracing members carried by said brackets.
21. A bulkhead for the purposes herein set forth including a supporting member mounted for movement transversely with respect to a freight car and having a longitudinally extending groove formed therein, brackets having pin members working in said groove and adapted to engage sockets formed in said member for holding said brackets in operative position, and bracing members carried by said brackets for vertical pivotal movement.
22. A bulkhead for the purposes herein set forth including a supporting member mounted for movement transversely with respect to a freight car and having a longitudinally extending groove formed therein, brackets having pin members working in said groove and adapted to engage sockets formed in said member for holding said brackets in operative position, and bracing members carried by said brackets adapted to be pivoted into and out of bracing position, means for locking said bracing members out of bracing position, and means for locking said bracing members in bracing position.
23. A bulkhead for the purposes herein set forth including a supporting member, bracing members carried by said supporting member for movement longitudinally with respect thereto and for vertical pivotal movement, and means permitting movement of said support from operative position.
24. In combination with a freight car, a supporting post mounted upright within said car, and a plurality of brace bars spaced and mounted transversely on said supporting post, to form a partition, and adapted to be swung on said post and arranged parallel therewith, and adjacent thereto, out of operative position.
25. In combination with a freight car, supporting means mounted within the car, bracket means mounted on said supporting

means, and partition means mounted on said bracket means, said partition means being arranged to be swung on said bracket means and moved parallel with said supporting means and adjacent thereto out of operative position.

26. In combination with a freight car, supporting means mounted within the car, bracket means mounted on said supporting means, partition means mounted on said bracket means, said partition means being arranged to be swung on said bracket means and moved parallel with said supporting means and adjacent thereto out of operative position, and means for locking said partition means in said parallel inoperative position.

27. In combination with a freight car, supporting means mounted within said car, bracket members mounted for movement longitudinally on said supporting means, and partition members movably mounted on said bracket members and adapted to be arranged parallel with said supporting means and to be adjusted longitudinally with said bracket members on said supporting means, one of said partition members having its free end supported on another of said bracket members when adjusted in inoperative position.

28. In combination with a freight car, a track mounted in said car, supporting means mounted to move along said track, and partition members mounted to swing on said supporting means and arranged to extend

transversely thereof in their operative position and to be folded longitudinally against said supporting means and moved therewith to a wall of said car out of operative position.

29. In combination with a freight car, a track mounted in said car, supporting means mounted to move along said track, partition members mounted to swing on said supporting means and arranged to extend transversely thereof in their operative position and to be folded longitudinally against said supporting means and moved therewith to a wall of said car out of operative position, and means for locking said mechanism against said car wall.

30. In combination with a freight car, a track mounted within said car, supporting means mounted to move along said track, partition members mounted for swingable movement on said supporting means, and being foldable thereagainst in their inoperative position, means for locking said partition members in such folded position, said mechanism being movable against a wall of the car out of operative position, and means for locking said mechanism against said car wall in such operative position.

In testimony whereof I have signed my name to this specification in the presence of two subscribing witnesses.

WILLIAM J. LAFFEY.
